UNITED STATES PATENT OFFICE.

JOSIAH B. REDFIELD, OF NORTH PLATTE, NEBRASKA.

MOUTH-GAG.

1,252,177.

Specification of Letters Patent.

Patented Jan. 1, 1918.

Application filed July 23, 1917. Serial No. 182,191.

To all whom it may concern:

Be it known that I, JOSIAH B. REDFIELD, a citizen of the United States, residing at North Platte, in the county of Lincoln and 5 State of Nebraska, have invented certain new and useful Improvements in Mouth-Gags, of which the following is a specification.

The present invention relates to means for 10 holding the jaws of a patient separated, or in other words, the mouth in open condition for the purpose of treating the throat and other allied parts, and the object is to provide in connection therewith a tongue de- 15 pressor of a simple and effective character that constitutes a part of the gag or jaw holding means, said depressor being readily adjustable to different conditions, and the parts being so disposed that they are not in 20 the way, and are readily accessible.

The preferred embodiment of the invention is illustrated in the accompanying drawings, wherein:—

Figure 1 is a perspective view of the de- 25 vice,

Fig. 2 is a cross sectional view, and

Fig. 3 is a detail underside view of the tongue engaging portion of the depressor.

Similar reference numerals designate cor- 30 responding parts in all the figures of the drawings.

In the embodiment disclosed, a pair of jaw separating members 4 and 5 are em- 35 ployed that are pivoted together at their ends, as shown at 6 and 7. These members or jaws are generally of bow shape and are relatively rigid. The upper jaw 4 has a central inset loop portion 8 for engagement with the upper jaw and lip and the lower 40 jaw 5 has a correspondingly shaped loop portion 9. Operating levers 10 are connected to the jaws at one end and terminate beyond the same in coöperating finger pieces 11.

For the purpose of holding the jaws in 45 separated position, ratchet levers 12 are employed, said levers being pivoted at their upper ends to the upper jaw 4, as shown at 13, and having on their outer sides ratchet teeth 14 arranged to engage keepers 15 through which said levers slide, the keepers being carried by the lower jaw 5. In order 50 to insure the engagement of said teeth with the keepers, coiled springs 16 connected to the upper jaw 4 are also connected to the levers 12.

The lower jaw 5 is provided at the inset

jaw engaging loop portion 9 with spaced bars 17 forming a guideway in which is slidably mounted a curved leaf stem 18. The rear end of this stem terminates in a relatively flat broad plate 19 preferably having openings 20 therethrough and having its under side provided with a series of corrugations 21. Threaded through the upper bar 17 is a set screw 22 that is arranged to 65 bear against the leaf stem 18 for the purpose of securing the same in any desired adjusted position. The head of this set screw is exposed and accessible in the inset loop portion 8 of the upper jaw 4 when the 70 jaws are together.

The use of the instrument will be obvious to those skilled in the art. The jaws are placed together and arranged in front of the patient's mouth with the inset loop portions 75 19 between the teeth, the tongue depressor being suitably adjusted. Upon bringing the finger pieces 11 together, the jaws 4 and 5 will be separated and will be held in separated position by the ratchet levers 12. The 80 mouth of the patient is thus entirely unobstructed while the tongue is firmly held depressed, and it will be evident that by adjusting the stem 18 in the guideway, the in- clination and disposition of the plate 19 can 85 be varied to suit the particular conditions met with.

From the foregoing, it is thought that the construction, operation and many advantages of the herein described invention will 90 be apparent to those skilled in the art without further description, and it will be understood that various changes in the size, shape, proportion, and minor details of construction may be resorted to without depart- 95 ing from the spirit or sacrificing any of the advantages of the invention.

Having thus fully described my invention, what I claim as new, and desire to secure by Letters Patent, is:—

1. In an instrument of the character set forth, the combination with relatively movable jaw separating members, of a tongue depressor member including a stem provided with a curved portion that is slidably en- 105 gaged with one of the jaw separating members to cause the member to assume different angular relations upon its sliding movement.

2. In an instrument of the character set forth, the combination with pivotally connected jaws, one having an intermediate guideway, of a tongue depressor plate hav-

ing a curved leaf stem slidable in the guideway and upon its sliding movement effecting a change in the angular position of the plate with respect to the jaw carrying it, 5 and means for securing the stem in different positions.

3. In an instrument of the character set forth, the combination with pivotally connected members having central inset jaw and 10 lip engaging projections, one of said projections having a fixed guideway, of a tongue depressor member including a curved stem portion slidable in the guideway and rotatable with respect to the jaw carrying it, 15 and means for securing the stem portion against sliding movement.

4. In an instrument of the character set forth, the combination with pivotally con-

nected jaw separating members having central inset jaw and lip engaging loops, one of 20 said loops having a fixed guideway, a tongue depressor plate having a curved stem portion slidable in the guideway to cause the plate to assume different angular relations with respect to the jaw carrying it, and a 25 set screw threaded into the inner side of the guideway and engaging the stem portion for holding it in different positions, said set screw being accessible in the loop of the other member when the jaws are closed. 30

In testimony whereof I affix my signature in the presence of two witnesses.

JOSIAH B. REDFIELD, M. D.
